[57] CLAIM

The ornamental design for a computer workstation, as shown and described.

DESCRIPTION

FIG. 1 is a front perspective view of the computer workstation showing our new design;

FIG. 2 is a front elevational view thereof on an enlarged scale;

FIG. 3 is a rear perspective view thereof on an enlarged scale;

FIGS. 4 and 5 are respectively left and right side perspective views thereof on an enlarged scale;

FIG. 6 is a top plan view thereof on an enlarged scale;

FIGS. 7 and 8 are respectively left and right side perspective views of a second embodiment of our new design;

FIG. 9 is a rear perspective view thereof; and

FIG. 10 is a top plan view thereof.

The front of the second embodiment is identical to that of the first embodiment as shown in FIGS. 1 and 2.
